[57] CLAIM

The ornamental design of a combined bottle cap and foil remover, as shown and described.

DESCRIPTION

FIG. 1 is a perspective view of a combined bottle cap and foil remover showing my new design; FIG. 2 is a front elevational view thereof; FIG. 3 is a side elevational view thereof; and, FIG. 4 is a top plan view thereof.

The hand and bottle are shown in broken lines for illustrative purposes only. The undisclosed rear view is unornamented.
